UNITED STATES PATENT OFFICE

141,009

DESIGN FOR A DOLL CRADLE

Robert Holmes Greenwell, Washington, D. C.

Application December 27, 1944, Serial No. 117,113

Term of patent 7 years

(Cl. D5—5)

To all whom it may concern:

Be it known that I, Robert Holmes Greenwell, a citizen of the United States, residing at 4115 W Street, N. W., in the city of Washington, District of Columbia, have invented a new, original, and ornamental Design for a Doll Cradle, of which the following is a specification, reference being had to the accompanying drawing, forming part thereof.

Figure 1 is a side perspective view of a doll cradle showing my new design;

Figure 2 is a side elevational view; and

Figure 3 is a top plan view thereof.

Both sides in Figures 1 and 2 are identical.

I claim:

The ornamental design for a doll cradle, as shown and described.

ROBERT HOLMES GREENWELL.
